UNITED STATES PATENT OFFICE

FRANK L. FURBUSH, OF GRANITEVILLE, MASSACHUSETTS, ASSIGNOR TO C. G. SARGENT'S SONS CORPORATION, OF GRANITEVILLE, MASSACHUSETTS, A CORPORATION OF MASSACHUSETTS

DRIER

Application filed March 14, 1932. Serial No. 598,776.

This invention relates to a drying machine for drying purposes in general but it is particularly applicable to a machine for drying fibrous material such as wool.

5 The principal object of the invention is to provide improved means for directing fresh air from the outside to a proper point to cool the stock and prevent the hot air in the machine from going out into the room and also 10 to provide for proper regulation of the air so that fresh air can be admitted at another point if found necessary to reduce the pressure of the air on the stock on the conveyor or apron which carries it through the machine.

15 Other objects and advantages of the invention will appear hereinafter.

Reference is to be had to the accompanying drawing, in which

20 Fig. 1 is a longitudinal sectional view through the whole length of a drier constructed in accordance with this invention, and

25 Fig. 2 is a sectional view on the line 2—2 of Fig. 1.

The invention is shown as applied to a 30 drier of well-known type in which the material is fed from a bin 10 by means of an automatic feeder 11 therein and deposited on the main conveyor or apron 12 in the drier. This latter apron conveys the material in a loose condition through the drier to the doffer end where it passes over a cylinder or drum 13 which also supports that end of the end-

35 less conveyor. Above the long working strand of the conveyor 12 are located steam-heating pipes 14 in a compartment of the usual character. Below the conveying strand of the

40 apron 12 but at one side are located fans 15 usual which are designed to draw in the fresh air at the doffer end of the drier and force it upwardly over a partition 16 and then downwardly through the pipes 14 and through the fibrous material on the top strand

45 of the apron 12. The air for this purpose comes in at the doffer end as stated.

It is a well-known expedient to let the air in at the doffer end over the material on the apron 12 and through a partition 17 which is 50 provided with an opening having a damper

18 for regulating the amount of fresh air admitted. This construction by itself permits the air after it is heated in the drier to blow out into the room through the opening in the partition 17. Furthermore, the air 55 coming in over the material on the conveyor at the doffer end may be drawn in so rapidly by the series of fans 15 located along the side of the drier as to press the stock down on the conveyor and not allow enough air to go down 60 through it.

By this invention, an additional partition 20 is employed spaced from the partition 17 and close to the doffer end of the machine. This partition extends all the way from the 65 bottom of the drier to a point just under the upper strand of the apron having of course an opening through it for the lower strand and apron. It is provided with an opening through it and a damper 21 which 70 can be opened more or less or closed entirely according to the circumstances by means of a shaft 22 and hand wheel 23.

It will be seen that by this arrangement a compartment 24 between the partitions 17 75 and 20 is provided which is substantially enclosed. Now the air coming in through the stock on the conveyor at the top of this compartment in the old way can be regulated by means of the damper 21. If the pressure of 80 the air is too great on the stock on the apron above the compartment 24, the damper 21 can be opened as much as may be desired to allow air to enter at that point and reduce the pressure of the air from above on the stock. At all times a considerable body of air will be drawn in through the stock from above to cool it. This construction also prevents the hot air in the machine from blowing out into the room and thus reduces the 85 expense of operation.

This furnishes a very simple and inexpensive construction for accomplishing these objects. It increases the efficiency of the drier and enables the current of air pressing 95 on the stock at the doffer end to be regulated whenever necessary to secure the proper cooling of the stock by this air before the stock is discharged from the machine.

Although I have illustrated and described 100

only one form of the invention, I am aware of the fact that modifications can be made therein by any person skilled in the art without departing from the scope of the invention as expressed in the claims. Therefore, I do not wish to be limited to all the details of construction herein shown and described, but what I do claim is:—

1. In a drier, the combination with a casing, an apron therein for passing the stock through the drier, means for heating the drier, fans for drawing in the air from outside, a partition in the casing having a damper located at a distance from the doffer end for admitting the air to the fans, means for admitting air to the drier through the stock

at the doffer end, and a second partition nearer the doffer end than the first one having a damper for regulating the pressure of air on the top of the stock.

2. In a drier, the combination with a casing, an apron therein for conveying the stock through the drier, of two partitions near the doffer end of the casing separated from each other, each having an opening provided with a damper and the drier having an opening above the stock at the doffer end, whereby the damper in the partition nearest the end can be used to regulate the amount of air which is admitted from above the stock and its pressure on the stock.

FRANK L. FURBUSH.
